Attorney,

UNITED STATES PATENT OFFICE.

WILLIAM FIELDS, OF TRENTON, NEW JERSEY.

LOCK.

1,106,292.

Specification of Letters Patent.

Patented Aug. 4, 1914.

Application filed September 12, 1913. Serial No. 789,539.

To all whom it may concern:

Be it known that I, WILLIAM FIELDS, a citizen of the United States, residing at Trenton, in the county of Mercer and State 5 of New Jersey, have invented new and useful Improvements in Locks, of which the following is a specification.

This invention relates to door operating and locking mechanism and the essential 10 feature of the device is to provide means whereby the door is locked from the inside and can be only opened upon manipulation of mechanism arranged upon the inside of the door.

15 A further object of the invention is the provision of novel locking and operating means for doors which is arranged on the inside thereof and away from the free edge of the door so as to prevent the insertion of 20 tools for opening the same, thus making a perfectly burglar proof door.

Further objects of the invention will appear as the following description is read in connection with the accompanying drawing, 25 which forms a part of this application, and in which—

Figure 1 is a front elevation showing the device applied to a cellar door with the door in fully open position. Fig. 2 is a vertical 30 section taken approximately on the line 2—2 of Fig. 1, showing the door closed and the latch in operative position. Fig. 3 is a bottom plan view.

Referring more particularly to the drawing, 1 represents a suitable support which may either be a portion of the door frame 2 or a part of a horizontal wall, as will be readily understood. Secured to the support 35 is a bearing member 3 having pivoted thereon a hinge arm 4 which is pivotally connected to the door 5 through an arm plate 6 secured to said door. The arm 4 has mounted thereon a suitable rib or keeper 7 which is engaged by the hooked end of the pivoted 40 catch member 8 pivoted in the ears formed on the bearing member 3. This catch 8 normally has its hooked end thrown into engagement with the keeper 7 by means of a spring 10 and automatically assumes a locking 45 position when the door is closed.

In order to open the door there is journaled in suitable bearings upon the support 1 a shaft 11 which may be operated either by a lever or by a weight 12 connected to 50 a cable 13 which is in turn wound around

the shaft 11. This cable is arranged to rotate the shaft in one direction and wound around the shaft are a pair of cables 14 which extend beneath the bearing member 3 and are connected to eyes 15 on the underside of the arm 4 so that immediately upon release of the catch 8 the arm 4 will be thrown outwardly or upwardly until the underside of the arm engages the support 1. The door may then be turned upon its pivotal connection with the arm to the position shown in Fig. 1. Upon closing the same against the tension exerted by the weight the hook member 8 will lock the arm 4 against movement and thereby prevent opening of the door. If desired, the catch may be held in operative position in any suitable manner so as to prevent the automatic locking of the door when closed. This may be accomplished by pivoting a link 16 to the bearing member which will engage over the end of the catch 8, as will be readily understood.

It will be noted that when the door is in closed position that it can not be turned upon its pivotal connection with the arm 4 owing to the fact that the inner edge of the door abuts against the jamb or frame and precludes any movement of the door until the catch is released. Where it is only desired to open the door a short distance, the arm may be made solid with the arm plate 6.

What is claimed is:—

1. In a device of the class described, the combination with a door frame and a door, 90 of hinge members secured to the frame and the door, an intervening curved arm member connected to said hinge members and pivoted to one of them and means carried by one of the hinge members for locking the 95 arm member against movement.

2. In a device of the class described, the combination with a door frame and a door, 100 of hinge members secured to the frame and the door, an intervening curved arm member connected to said hinge members and pivoted to one of them, means carried by one of the hinge members for locking the arm member against movement, and means connected to the arm member and adapted to 105 raise the hinge member on the door and the door when the locking means is released.

3. In a device of the class described, the combination with a support and a door, of hinge members secured to the support and 110

the door, a curved arm member pivoted to each of the hinge members and adapted to turn the door over the support, means for locking the arm member against movement and means for pivoting the arm member upon one of the hinge members when the locking means is released.

In testimony whereof I affix my signature in presence of two witnesses.

WILLIAM FIELDS.
